United States Patent Office.

MATTHEW BENNETT, OF KILBOURNE CITY, WISCONSIN.

Letters Patent No. 60,673, dated January 1, 1867.

IMPROVED DOOR FASTENING.

The Schedule referred to in these Letters Patent and making part of the same.

TO ALL WHOM IT MAY CONCERN:

Be it known that I, MATTHEW BENNETT, of Kilbourne City, in Columbia county, and State of Wisconsin, have invented a new and improved Door Fastener or Lock, to be used on doors and on drawers; and I do hereby declare that the following is a full, clear, and exact description thereof, reference being had to the accompanying patterns, and to the figures of reference marked thereon.

Four things are necessary to the design of the said door fastener or lock, which four things are each claimed to be new and original inventions, and without any one of which the said door fastener or lock would be incomplete, viz:

1. A spring-latch marked "1," in the parcel labelled "patterns," one end of which is made like the blade of a lance; after boring a suitable depth into the door, the lance end of the latch is driven into the solid wood three-fourths ($\frac{3}{4}$) of an inch, as per model.

2. A bolt marked "2," in the parcel marked "patterns," uniting the knobs and working under and raising the latch marked "1;" an enlarged width in the centre of the bolt is required, as may be seen in the wooden pattern, and this enlarged width is claimed as new and valuable in its application, as may be seen by an examination of the model.

3. A stop or fastening marked "3," in the parcel labelled "patterns." Those applicable to bolts moving horizontally cannot be applied to bolts moving perpendicularly; hence a new, simple, and efficient stop or fastening has been invented, the construction and operation of which are explained as follows: The stop is constructed in the form of a capital "L." In the centre of the long arm of the "L," on the under side, is a notch which is intended to take hold of the plate on the outside, to keep it from passing back. The wood is so cut away in the door as that the part of the "L" or stop falls a little below the spring-latch when pushed in beyond the latch; and when the stop is drawn out the door is fastened; the latch cannot raise, as will be seen by reference to the model sent herewith.

4. A spring-catch marked "4," in the parcel marked "patterns." In order not to cut or mar the casing of the door, a spring-catch has been invented which gives way to the door till the latch marked "1" is opposite to the mortise in the catch, when the latter flies forward, takes the latch, and sinks into the plate on the door, which is counter-sunk. The model exhibits the catch made in a cheap mode; but a neater mode of making them may be seen by reference to pattern marked "4." Iron is sufficiently elastic for all the springs.

Both the spring-latch and spring-catch are claimed as new and valuable inventions, intended to supersede the spiral and other springs, and the complicated arrangements of locks and fastenings now in use, which are expensive and liable easily to get out of repair; and the wide knob-bolt and stop are claimed as new and valuable inventions, and are necessary to work the spring-latch and spring-catch aforesaid, and give them any actual value.

I claim the combination of the devices constructed and arranged as described.

MATTHEW BENNETT.
